(Cl. D26—1)

FIG. 1

FIG. 2

Fig. 1 is a perspective view of the data processing machine embodying my new design.

Fig. 2 is a front elevation of the same.

Fig. 3 is a right side elevation of the same.

The left side elevation is substantially the same as the right side.

The plan view has the longitudinal dimensions of Fig. 2 and the lateral dimensions of Fig. 3.

The rear elevation is substantially plain and has the longitudinal dimensions of Fig. 2 and the vertical dimensions of Fig. 3.

I claim:

The ornamental design for a data processing machine, as shown and described.
